UNITED STATES PATENT OFFICE.

OTTMAR A. GATRELL, OF COLUMBUS, OHIO, ASSIGNOR OF ONE-HALF TO
ROSA BAUM.

VOTING-MACHINE.

SPECIFICATION forming part of Letters Patent No. 617,734, dated January 17, 1899.

Application filed December 27, 1897. Serial No. 663,580. (No model.)

To all whom it may concern:

Be it known that I, OTTMAR A. GATRELL, a citizen of the United States, residing at Columbus, in the county of Franklin and State of Ohio, have invented certain new and useful Improvements in Voting-Machines; and I do hereby declare the following to be a full, clear, and exact description of the invention, such as will enable others skilled in the art to which it appertains to make and use the same.

A ballot under the Australian system of voting consists of a sheet of paper having printed in several vertical rows thereon the names of the nominees of the respective parties, and it is required of the voter to designate by a pencil-mark at the top of the ticket an entire ticket, if he wishes to vote it, or by marks opposite the name of each and every particular nominee for whom he wishes to vote if he wishes to vote a "scratched" or mixed ticket. After the polls are closed it is required of the judges of election to count the ballots and the number of votes received by each candidate, and this has proved an arduous and time-consuming process, particularly when there has been much "scratching," delaying the returns and taxing the patience of an anxious public.

The object of my invention is to provide a voting-machine of simplified construction in which the use of separate paper ballots and a pencil are avoided and in which the voting is accomplished by simply pushing keys, and, further, in which the voting is expedited by reason of devices under the observation and control of the judges, indicating when the voter has finished his vote.

Machines for mechanically registering votes have heretofore been devised, but owing to their complexity and the absence of certain characteristics necessary to the successful and satisfactory operation and use such machines have failed of adoption. With my machine as here shown the voter is simply required to push a button near and opposite the name of each nominee, and incidentally I provide means for rendering it impracticable to vote for more than one nominee for any particular office and therefore impracticable for him to vote for more than the proper number of

nominees. Hence it will be gathered that it will be impracticable for a voter to vote a defective and incompetent ballot, as is frequently now the case with the ordinary paper ballot.

In the annexed drawings, Figure 1 is a front view in elevation of a machine embodying my invention, parts being broken out to illustrate details of the interior mechanism. Fig. 2 is a vertical sectional view on a plane indicated by the line $\alpha\alpha$, Fig. 1, the uppermost spool being broken off and the ribbons or tapes of all the spools being omitted except the lowermost. Fig. 3 is a horizontal sectional view illustrating the key and register device. Fig. 4 is a detail illustrating the details of construction of the bar for operating the vote-indicator wheel. Fig. 5 is a detail view, in front elevation, of the device for lifting the pawls that latch the push-buttons or key-bars. Fig. 6 is a vertical sectional view of a voting-booth, illustrating how my machine may be used.

Like characters of reference in the different views designate corresponding parts.

1 designates the casing or frame in which all the parts are mounted. The said casing or frame may be provided with a horizontal partition 2, lying about midway of the casing.

Arranged in the lower compartment so as to stand in vertical and horizontal rows are key-bars 3, having at their protruding outer ends buttons or keys 3^a. These vertical rows are spaced sufficiently far apart to allow places 4 in which to place and exhibit adjacent each key the name of the nominee, as well as the office for which he is a candidate. In practice there will of course be provided in the machine as many horizontal rows of keys as there are offices to be voted for and as many vertical rows as there are parties having nominees. The inner ends of the key-bars 3 are provided with small peripherally-grooved rollers 3^b.

Supported to stand vertically in the machine and in line with the inner ends of each of the vertical rows of keys is a bar 5, having a series of teeth 5^a pivoted in the upper portion thereof, and in the lower end of said bar 5 is a peripherally-grooved pulley 5^b, the axle of

which protrudes and moves in guide-bars 6, depending, preferably, from the horizontal partition 1. Arranged vertically near the inner ends of each of the vertical rows of the bars 3 are standards 7, which support idler-rollers 7^a, that are spaced to allow the bars 3 to be pushed horizontally between them. Attached to the under side of the partition 2 is a cord 8, that passes downward under the roller 5^b, upward to and over pulleys 9 on the partition 2, and thence downward between the rollers 7^a in standards 7 and rollers 3^b in the key-bars 3 to the bottom of the casing, where it is tied.

15 Arranged horizontally in the upper rear part of the casing is a shaft 10, upon which are keyed as many ratchet-wheels 10^a as there are bars 5. Said ratchet-wheels have as many teeth as there are keys in a vertical row and 20 they are positioned on the said shaft to be engaged and operated by the teeth of said bars 5. There is also secured on said shaft at any suitable point between two of the ratchets a drum 11, bearing on its circumference a series 25 of numbers from "1" upward to as many as there are teeth on the ratchet-wheels. The ratchet-wheels are engaged by spring-actuated pawls 10^b, pivoted in the upper side of the casing, and the drum 11 has a pin 11^a to engage a stop 11^b on the upper side of the casing to prevent it from making more than one rotation or to limit the rotation thereof at any point desired.

Arranged in the front part of the casing 35 alongside of each vertical row of key-bars 3 is a stationary shaft 12, upon which is a series of spools 13, each having a ratcheted head 13^a, that stands in a horizontal plane with one of the bars 3. These spools rotate on the 40 shaft 12 independently of one another, and each of the ratcheted heads is engaged by a pawl 14, pivoted in the wall of the casing, that permits the spools to be rotated from left to right only. Each of the bars 3 is provided with a tooth 3^c to operate the ratcheted head of the spool and is so placed that when 45 the key is in its outermost position it shall not strike a tooth of the ratcheted head until the key has been pushed considerably inward. Each of the key-bars 3 is provided at its under side with coiled springs 3^d to retract it at the proper time after it has been pushed in.

Pivoted on vertically-arranged bars 15 are 55 pawls 15^a, that drop into and engage notches 3^c in the upper edges of the key-bars 3 when said bars have been pushed in sufficiently far to register a vote.

In Fig. 5 I have shown a structure that I 60 have devised for lifting simultaneously all the pawls 15^a. It consists of a frame made up of the upper and lower horizontal rails or parts 16 and 16^a and several pairs of vertical strips 16^b, between which latter are passed 65 as many small horizontally-arranged pins 16^c as there are pawls 15^a. This frame, which may not improperly be termed the "key-re-

leaser," is so constructed and placed in the machine that one of the pins 16^c shall stand transversely under each of the pawls 15^a, yet not so as to prevent the dropping of the said pawls into the notches of the key-bars 3. The said frame is movable vertically, and to keep it in its proper position the lower rail 16^a projects slightly at each end, as shown at 16^a, 75 to engage channels or grooves in the opposite side of the casing. The upper part of the frame passes through and is guided by a narrow row opening in the partition 2. A cord 17 is attached to the middle of the upper rail 16^a and passes over a pulley in the wall of the casing 1. Each of the spring-actuated pawls 10^b also has attached to it a cord 12^a, that passes out through the top of the casing 1 and over a pulley, and the several cords 12^a are 80 attached to common bar 12^c. The cord 17 is also attached to the bar 12^c, and from this bar extends a cord 18, so that the key-releaser and the pawls 10^b may be operated simultaneously and, if desired, in a room adjoining 90 that in which the voting-machine is placed, as indicated in Fig. 6.

As before stated, the names of the nominees of the different parties for the same office are arranged in the same horizontal line, 95 and to prevent a voter from voting for more than one nominee (thereby rendering his vote void for uncertainty) I provide means for making it impracticable for him to push in more than one key a distance sufficient to operate the ratcheted head of the spool 13. This means in the instance shown consists of a cord 20, passed horizontally through the holes 3^b in each of the horizontal rows of keys. This cord is made of such length or is tied to the 105 opposite side walls of the casing in such manner that the slack permits one key-bar only to be pushed in sufficiently far to effect an operation of the spool 13. The ends of the holes 3^b are preferably rounded to prevent 110 the cutting of the cord 20.

In the rear part of the lower compartment are arranged vertical stationary shafts 21, upon which are placed independently-movable spools 22, having ratcheted heads 22^a. 115 There are as many of the shafts 21 as there are shafts 12 and as many spools 22 as spools 13, and said spools occupy the same horizontal plane. The ratcheted heads of the spools 22 are also engaged by spring-actuated pawls 120 to prevent them from rotating in more than one direction. Each of these spools 22 contains a tape 23, bearing numbers from "1" upward, which are so spaced that one number is brought to a given point upon each movement of the spool 13, to which the free end of said tape is attached. In the drawings I have shown but one of these tapes. The front of the casing is provided with vertical slits 24, through which the numbers on the 130 tapes may be seen. The several spaces along the vertical rows of keys are provided with channels 25, into which the ticket bearing the names of the nominees may be slid. The

ticket may be protected by a strip of glass fitting between the channels and covering and protecting the ticket, but so that it may be seen by the voter.

5 In operation the voter, if found duly qualified, passes into the room containing the machine and pushes in the keys opposite the names of the nominees for whom he intends to vote. In Fig. 2 I have shown one of such 10 keys pushed in. It is the fifth key from the top. When a key is thus pressed in, it pushes the cord 8 inward between the rollers 7^a and raises the bar 5 a distance of one tooth, thus turning the drum 11 one tooth and exhibiting 15 a number. The pushing in of a key-bar also moves the adjacent spool 13 one tooth and winds the tape on the said spool the space of one number.

With the apparatus shown eleven votes 20 only can be had by any voter until the apparatus is reset by the judges of election, and the operation of any eleven of the keys in different horizontal rows effects a complete revolution of the drum 11. When eleven 25 votes have been made by the voter the number "11" is exhibited through an opening in the casing and partition to the judges of election in the adjoining room, who then know that the voter has finished. The voter is of 30 course required to finish his vote within a prescribed time, and the machine is reset by the judges of election by simply pulling upon the cord 18, thus lifting the key-releaser, the keys automatically returning to their outward position through the operation of their 35 springs 3^a. When the cord 18 is pulled, the pawls 10^b are also lifted, thus allowing the bars 5 to drop by gravity, the pivoted teeth therein readily passing the teeth of the 40 ratchet-wheels 10^a.

The several vertical rows of keys may, if desirable or advantageous, be differently colored to distinguish the tickets of the several political parties.

45 When the polls are closed, the judges of election remove the tickets from the channels 25 and take down the number of votes received by each nominee, as shown by the tapes through the slits 24, and make their 50 report to the proper authorities.

The key-bars 3 may be sustained in their horizontal position by means of pins 26, secured and extending between the bars 15 and passing through slots 3^c in the key-bars 3.

My machine as shown in the accompanying 55 drawings is susceptible of modification without departing from the scope of my invention.

Additional keys like those already herein shown and described may of course be also 60 provided to enable voters to vote "yes" or "no" upon propositions submitted to the suffrage of the people.

What I claim, and desire to secure by Letters Patent, is—

1. In a voting-machine, the combination of 70 a series of keyed push-bars arranged in horizontal and vertical rows, means for registering the number of times each push-bar is operated, cords 20 adapted to prevent the operation of more than one push-bar in each row, shaft 10, indicator-wheel 11 and a series of ratchet-wheels 10^a on said shaft, toothed bars 5 engaging the ratchet-wheels, and cords 8 arranged to engage the bars 5 and to be operated 75 by the push-bars, substantially as and for the purpose shown and described.

2. In a voting-machine, the combination of 80 a series of keyed push-bars arranged in horizontal and vertical rows, means for registering the number of times each push-bar is operated, locking-pawl 15^a for the push-bars, frame 16 adapted to release all the pawls 15^a simultaneously, shaft 10, indicator-wheel 11 and a series of ratchet-wheels 10^a on said 85 shaft, toothed bars 5 engaging the ratchet-wheels, cords 8 arranged to engage the bars 5 and to be operated by the key-bars, pawls 10^b for the ratchet-wheels, cords 12^a for releasing pawls 10^b, cord 17 for raising frame 90 16, and cord 18 connected with cords 12^a and 17 for releasing pawls 15^a and 10^b simultaneously, substantially as shown and described.

In witness whereof I have hereunto affixed my hand, this 14th day of December, 1897, in 95 the presence of two witnesses.

OTTMAR A. GATRELL.

Witnesses:

GEORGE M. FINCKEL,

FRED C. RECTOR.
